DESIGN FOR A HANDBAG

Ludwig S. Schlessinger, New York, N. Y.

Application September 27, 1944, Serial No. 115,477

Term of patent 3½ years

(Cl. D87—3)

To all whom it may concern:

Be it known that I, Ludwig S. Schlessinger, a citizen of the United States, residing in New York, in the county of New York and State of New York, have invented a new, original, and ornamental Design for a Handbag, of which the following is a specification, reference being had to the accompanying drawing forming a part thereof, wherein:

Fig. 1 is a perspective view of a handbag embodying my new design; and

Fig. 2 is a bottom front perspective view thereof.

I claim:

The ornamental design for a handbag, substantially as shown.

LUDWIG S. SCHLESSINGER,
